Inventor:
William J. Forster,

Eccleston & Eccleston.

Attys.

UNITED STATES PATENT OFFICE.

WILLIAM J. FORSTER, OF DALLAS, TEXAS.

REGULATOR FOR GASOLINE ENGINES.

Application filed October 8, 1921. Serial No. 506,351.

To all whom it may concern:

Be it known that I, WILLIAM J. FORSTER, a citizen of the United States, residing at Dallas, in the county of Dallas and State 5 of Texas, have invented certain new and useful Improvements in Regulators for Gasoline Engines, of which the following is a full, clear, and exact description.

My invention relates to a regulator or adjustable means to be used in connection with gasoline engines and has for its object to provide such a device which may be placed between the carbureter and intake manifold of the engine.

It is quite often desirable in connection with automobiles, especially taxi-cabs and the like, to have some means to limit the speed at which they may be driven and I have accordingly devised the present invention which is, in effect, a valve for regulating the amount of fuel which may pass to the engine.

In the drawing;

Figure 1 is a side view of a portion of an engine and carbureter with my attachment in place.

Figure 2 is a section on line 2—2 of Figure 1.

Figure 3 is a plan view of the attachment 30 with the valve in open position; and

Figure 4 is a longitudinal section through the valve, the same being shown in closed position.

Referring to the drawing more in detail, 35 the numeral 1 designates the intake of an internal combustion engine. Attached to the lower end 2 of the intake is a carbureter 3.

Clamped between the carbureter 3 and 40 intake 2 is a gasket 4 which may be made of metal or other suitable material. The

gasket 4 is provided with the usual openings 5 for the reception of the attaching bolts 6. Formed near the center of the gasket are two openings 7, although a 45 greater or less number may be provided as desired. A plate 8 having the wings 9—9 is pivoted at the center of the gasket by means of the bolt 10.

In operation the plate 8 is turned to the 50 desired position, i. e., the position which will let in sufficient fuel to make the maximum speed required. The gasket is then put in position against the end of the intake and the carbureter is bolted in place.

In accordance with the patent statutes I have described what I now believe to be the best embodiment of the invention, but I do not wish to be understood thereby as limiting myself or the scope of the invention, as many changes and modifications may be made without departing from the spirit of the invention, all such I aim to include in the scope of the appended claims.

What I claim as new and desire to secure by Letters Patent is:

1. A governor for gasoline engines comprising a flat gasket of sheet material adapted to be clamped directly between the carbureter and engine, and a valve mounted on 70 said gasket, said valve being free of projections and of less diameter than the inner diameter of the intake manifold.

2. The combination with the intake manifold and carbureter of an internal combustion engine, of a flat gasket of sheet material clamped in direct contact with both the intake manifold and carbureter, a valve mounted on said gasket, said valve being free of projections and of less diameter than 80 the inner diameter of the intake manifold.

WILLIAM J. FORSTER.
